UNITED STATES PATENT OFFICE

HARVEY B. LINDSAY, OF EVANSTON, ILLINOIS, ASSIGNOR TO DRY ZERO CORPORATION, OF WILMINGTON, DELAWARE, A CORPORATION OF DELAWARE

THERMOINSULATING STRUCTURE AND METHOD OF MANUFACTURING THE SAME

Application filed October 27, 1927. Serial No. 229,254.

My invention relates more particularly to the insulation of structures comprising a frame work, as for example, and more particularly, of relatively soft material, such as wood, defining the space to be insulated and forming openings into such space and in which the insulating material is located; one of the most common structures of this character being the ordinary refrigerator box refrigerated by ice, or by artificial refrigerating means.

These structures are commonly built with a sheet metal casing defining the refrigerating chamber and much difficulty has been heretofore encountered in effectually preventing the penetration of moisture-laden air from the atmosphere to the insulating material and the cold sheet metal casing, with the result that the insulating material becomes objectionably damp, particularly because of the condensation of the moisture on the casing, with the manifest objectionable results.

My primary object is to so form structures of the character above referred to, that circulation of air as above stated, with the above mentioned objectionable result, is prevented, whereby the insulating material is maintained comparatively dry in the continued use of the structure; to provide for the accomplishment of this result by simple and economical means and of such character that the structure may be readily and inexpensively built; and other objects as will be manifest from the following description.

Referring to the accompanying drawing showing my invention in connection with a refrigerator of the artificially cooled type:

Figure 1 is a perspective view of the frame-work of such a refrigerator. Figure 2 is a plan sectional view taken at the irregular line 2-2 on Fig. 1 and viewed in the direction of the arrow, this view showing the structure illustrated in Fig. 1 with the metallic refrigerating-chamber casing and the insulating body or unit for one of the frame-openings in position in the frame. Figure 3 is a cross sectional view of the insulating body or unit. Figure 4 is a similar view of the unit with the section being normal to that

shown in Fig. 3. Figure 5 is a view in section of one of the sides of the frame opening with the insulating body, or unit, shown in section and illustrating the preferred way in which the joint between the insulating body or unit and the frame, is effected; and Figure 6, an enlarged sectional view of certain of the parts shown in Fig. 5 and illustrating the form of joint produced.

Referring to the frame structure shown in the drawing, this is of common construction, it being formed of front uprights 7, rear uprights 8, and upper and lower cross members 10 and 11 defining at the upper portion of the frame a rectangular space 12 to receive the refrigerating-chamber-forming metal casing 13, and a lower space 14 in which the mechanism (not shown) for producing artificial cooling, is located. The frame thus formed presents the upper and lower rectangular horizontally disposed openings 15 and 16 and the vertically disposed openings 17.

The openings 15, 16, and the openings 17, except the one of the latter at the front of the frame, are provided for receiving bodies of insulating material, the opening 17 at the front of the frame, being provided to receive the door (not shown) as commonly provided in structures of this general character.

In practicing my invention, the insulating bodies, or units, for insulating the casing 13 and which would be positioned in the openings referred to in the frame to substantially fit therein, are represented at 18, these bodies, or units, being provided about their marginal edges at their outer faces with flange-portions 19 which extend outwardly therefrom continuously along the edges of each unit and overlap the faces of all of the walls of the frame openings in which the units are mounted, and are hermetically sealed in flat-wise condition to these walls to exclude moisture, by a suitable adhesive and in the manner hereinafter described.

The insulating bodies 18, which may be of any suitable construction, each comprises by way of example and preferably, a body 20 of fibers or strands in comparatively loose, or fluffy, condition, the maintenance of which

condition is desired, these strands by way of example being preferably kapok with the strands or fibers thereof preferably arranged to extend from end to end of the body 20 generally in the same direction as shown, and which it is desired be protected against moisture.

The bodies 18 are so constructed as to be sealed throughout their outer surfaces 10 against the access of moisture. In the construction shown, each body 20 of insulating material is located between sheets 21 and 22, the sheet 22 being of moisture-proof material, as for example, moisture-proofed paper, 15 with binding and confining strips 23 located at the edges of the body 20 parallel to which the strands or fibers of the body extend, these strips being sealed to the edges of the sheets 21 and 22 which they overlie. Extending entirely across the outer face of the sheet 22 and sealed thereto in any suitable manner, and of a size to provide the flanges 19, is a sheet 24 of moistureproof material, such as that referred to.

25 The sealing of the flange portions 19 to the flatwise-opposed surfaces of the frame-walls is effected by employing any suitable adhesive such for example any of the well-known asphaltum emulsions particularly 30 adapted to such use and tacky when cold.

In sealing the flanges 19 to the frame-work in accordance with my improved method as I prefer to practice it, I apply pressure against the outer surfaces of the flange portions 19 35 along areas extending crosswise of the path moisture would follow in entering the space occupied by the body 20 if not adequately sealed, and of widths less than the width of the flange portions, each flange portion being 40 preferably subjected to such pressure along a plurality of spaced apart areas, as distinguished from applying the pressure uniformly throughout the width of the flange portions as would result if a plain cylindrical roller, or flat-iron were used.

The pressure referred to is preferably applied by means of a roller presenting a series of corrugations extending circumferentially thereof, a suitable roller for this purpose being 45 shown at 25, the roller being journaled in a yoke member 26 provided with a handle 27 by which it may be grasped by the operator in rolling it along the flange portions 19 lengthwise thereof.

50 The operator in using the roller presses forcibly against the outer surfaces of the flange portions 19 and preferably with such force that the apex portions of the roller 55 forcibly compact the adhesive located between the flange portions 19 and the frame-work and represented at 28 causing the flange portions 19 to become corrugated in a direction lengthwise thereof and where the frame-work is of wood, or other relatively soft ma-

terial, also forming corrugations in the frame-work, as shown in detail in Fig. 6.

The forming of the joint as described has been found, in practice, to be highly effective in sealing the joint against access thereto of moisture. The pressure being applied by the roller along relatively narrow areas, the adhesive at these areas, between the flange portions 19 and the frame-work, is thus subjected to high pressure which results in closely compressing the adhesive along these areas and forming tight joints with the flange portions and frame-work. Furthermore, applying the pressure as stated operates to iron out any transverse creases which may be present 70 in the flange portions 19 and which if present would form channels, even though minute, through which moisture could penetrate into the space to be sealed. Also, by applying pressure to the flange portions 19 along spaced apart areas, the adhesive between these areas is trapped and thus prevented from squeezing 75 out with the manifest advantage.

Another advantage of forming the joints as described and which is a matter of considerable practical importance is that, whereas, it is almost impossible to detect an imperfect joint where the flange portions 19 are sealed by pressure applied thereto uniformly throughout their extent, it is only necessary, in inspecting a joint formed in accordance with my invention for determining whether or not a perfect seal exists, to observe whether or not the corrugating operation has been performed on the flange portions inasmuch as corrugating the joint ensures a perfect seal.

The forming of the corrugations in the frame-work, as described, serves to augment the sealing function. However, where the material of the frame-work is such, as for example where it is of metal, that the pressure applied by the operator through the roller is not sufficient to indent the frame-work, an effective seal will be produced and is likewise within my invention.

While I have described a particular method of producing the desired seal, I do not wish to be understood as intending to limit the invention thereto as the method may be varied without departing from the spirit of my invention.

What I claim as new, and desire to secure by Letters Patent, is:

1. The method of producing a hermetically sealed joint between flatwise opposed surfaces of elements to be united by an adhesive, one of the elements being flexible and the other a solid indentable body, which consists in rolling a corrugation in the flexible element and into the flatwise opposed portion of said solid indentable body while said elements are flatwise opposed with adhesive therebetween.

2. The method of producing a hermetical-

ly sealed joint between flatwise opposed surfaces of elements to be united by an adhesive, one of the elements being flexible and the other a solid indentable body, which consists in rolling corrugations in the flexible element and into the flatwise opposed portion of said solid indentable body while said elements are flatwise opposed with adhesive therebetween.

HARVEY B. LINDSAY.
